UNITED STATES PATENT OFFICE.

SALEM A. BAKER, OF INDIANAPOLIS, INDIANA, ASSIGNOR OF ONE-THIRD
TO JAMES A. STEWART, OF INDIANAPOLIS, INDIANA.

SLIDING-DOOR CONSTRUCTION.

No. 839,091.

Specification of Letters Patent.

Patented Dec. 25, 1906.

Original application filed May 25, 1905, Serial No. 262,147. Divided and this application filed December 7, 1905. Serial No. 290,835.

To all whom it may concern:

Be it known that I, SALEM A. BAKER, of Indianapolis, county of Marion, and State of Indiana, have invented a certain new and useful Sliding-Door Construction; and I do hereby declare that the following is a full, clear, and exact description thereof, reference being had to the accompanying drawings, in which like letters refer to like parts.

This application is divided out of an application filed by me May 25, 1905, Serial No. 262,147, for car-doors.

The object of this invention is to provide a convenient means for holding the lower ends of car-doors in place at all times, whether the door be closed or open, to prevent the same from flying outward while the car is moving, thus causing great damage.

To this end, a vertically-slidable angular bolt that is not oscillatory is provided that drops in behind the lower track when the door is closed and that may be elevated above the track for opening the door. Said bolt is also provided with a downward extension on its lower end that engages the lower track and limits the outward movement of the door, so that the door can swing outwardly only far enough to permit it to be moved longitudinally. This prevents the doors swinging while a car is moving.

The various features of the invention will be understood from the accompanying drawings and the following description and claims.

In the drawings, Figure 1 is a front elevation of a car-door provided with my invention. Fig. 2 is a vertical transverse section through the car-door and adjacent parts of the framework, the central part of the door being broken away and the door being shown in its closed position. Fig. 3 is a similar section of the lower part of the door and lower rail, the door being partially open or swung out at the lower end. Fig. 4 is a transverse section on the line 4-4 of Fig. 1 through the attachment to the lower part of the door for carrying a sliding bolt. Fig. 5 shows the lower part of Fig. 2 with the door in its outer position.

In detail, 10 represents a stock-car, and 11 is the door. It has hangers 12, supported by and movable upon the upper rail 13, that is secured to the frame of the car by the arms 14. There is also a lower track 15, carried on the arm 16.

Vertical bolts 17 are slidably mounted in a bolt-holder formed of the plates 18 and 19, that are secured to the door by the bolts and nuts 20. The plate 19 has two parallel flanges 21, between which the bolt 17 is placed. The flanges 21 are wide enough to hold the plate 18 out of contact with the bolt 17, so that said bolt will be readily movable vertically. The bolt 17 has a head 23 at its upper end, whereby it may be caught by the finger and elevated and whereby the bolt is prevented from escaping downward. Said bolt 17 is bent inward at its lower end to form a horizontal portion 24 and then downwardly to form the inner vertical portion 25. The lower surface of the part 24 has a notch or recess 26, that is adapted to fit over and ride upon the lower rail 15 when the door is in its outer position. Likewise the relation of the parts is such that when the bolt is in its lower position, as shown in Fig. 2, it will extend below the upper surface of the rail 15.

It is obvious that in its closed position the lower part of the door will be held in against the car by the lower rail 15 engaging the bolts 17. When it is desired to open or move the door, said bolts are elevated somewhat to the position shown in Fig. 3, so that they will ride upon the rail 15. In its outermost position the notches 26 of the bolt 17 will engage the upper edge of the lower track and prevent the door from moving either outwardly or inwardly, but permit the door to be laterally slidable. A flange 30 braces the parts 24 and 25 when the door is moved laterally. Thus it is seen that with this bolt arrangement the door is prevented from escape at its lower end whether in a closed or in an open position, and it cannot during the movement of the rail, and especially while going about a curve or passing other cars, swing outward and engage cars or other objects.

What I claim as my invention, and desire to secure by Letters Patent, is—

1. The combination with a car having a lower track for the door thereof, and a door slidably mounted on said car, of a bolt mounted in connection with the lower part of said door that is vertically movable and not oscillatory and has a horizontal inwardly-extending lower portion with a notch on the under side near its inner end and with a downward extension from its extreme inner end, the arrangement being such that the lower

end of the main portion of the bolt will engage the track while the door is closed and prevent the door swinging outward and while the door is in its outer position the notched portion of said bolt will prevent the door moving forward and the extreme lower extension of said bolt will prevent the door moving outward, substantially as set forth.

2. The combination with a car having a lower track for the door thereof, and a door slidably mounted on said car, of bolt-casings secured to the lower part of said door, bolts vertically movable in said casings and arranged so as not to be oscillatory with the lower ends bent inwardly to form horizontal portions and turned downwardly at their inner ends, the arrangement being such that the inner downwardly-extending portions of

said bolts always extend below the upper edge of said track, and the outer vertical portion of said bolts will extend below the upper edge of said track when the door is in its inner position, but which may be elevated above said track for permitting the movement outwardly of the lower part of the door, and a groove on the under side of the horizontal portion of each bolt adapted to fit over the upper edge of said track when the door is in its outer position.

In witness whereof I have hereunto affixed my signature in the presence of the witnesses hereinafter named.

SALEM A. BAKER.
